UNITED STATES PATENT OFFICE.

WILLIAM HIER, OF CANAANVILLE, OHIO.

INSULATING TUBE.

Application filed April 17, 1922. Serial No. 553,676.

To all whom it may concern:

Be it known that WILLIAM HIER, a citizen of the United States of America, residing at Canaanville, Ohio, in the county of Athens 5 and State of Ohio, has invented certain new and useful Improvements in Insulating Tubes, of which the following is a specification.

This invention relates generally to the 10 art of blasting in mining operations and particularly to a means for firing the shot or blasting cartridge.

One of the principal objects of my invention is to provide a charge or shot firing 15 appliance designed to isolate the match end of the squib from the combustible gases which escape from the drilled hole which receives said blasting charge, to the end that the entire match may not be instantly consumed and ignite the powder containing portion of the squib before the operator has had 20 an opportunity to depart to a point of safety before the charge is fired.

It will therefore be observed that the aim 25 of this invention is to provide a charge firing device which will permit of the usual functioning of the squib without danger of pre-ignition when used under conditions where marsh-gas particularly, is present 30 in the coal strata, and escapes to the mouth of the bore-hole at face of the wall.

Specifically, the invention contemplates a 35 device of tubular form preferably metal, adapted to be inserted for a portion of its length into the usual needle hole, which tubular device is provided with a series of longitudinally spaced radial apertures, which are so arranged that gases passing outwardly through the needle hole may be 40 permitted to escape at a point adjacent the mouth thereof and spaced from the point of ignition of the squib.

While the usual manner of firing charges 45 is of course well known to those familiar with mining operations, it might be well for the purpose of more clearly illustrating the use of my device as distinguished from the old method, to very briefly review the latter: According to the old method, after 50 the removal of the needle from the needle hole, the powder containing portion of the squib or fuse was inserted within said needle hole, the remaining two or three inches of the match end of the fuse extending without 55 the needle hole. The next step was to ignite the extreme free end of the match which is

designed to burn slowly enough to permit the operator to retire to a point at a safe distance from the place of blasting. This 60 operation was satisfactory and the fuse performed its function properly when there was an absence of gas from the bore hole. But, marsh-gas is quite often present and its presence can not always be determined, with the result that if present there is an 65 area of this highly combustible gas entirely enveloping the match end of the squib, and if the tip of the match end is ignited, there is an instantaneous combustion of this entire surrounding area of marsh gas. The 70 result is, that, instead of there being a slow burning of the match end of the fuse, it is ignited throughout its length immediately and the powder-carrying end of the fuse being thereby ignited almost simultaneously, 75 fires the blast, without a lapse of time sufficient for the miner to withdraw to a safe distance. This is commonly known as "pre-ignition" and often results in injury or possible death of the operator.

In contrast to the method just described, my device is designed to effectively maintain a lapse of time between the time of ignition of the match and the ignition of the powder carrying portion of the squib, and 85 whereby pre-ignition is rendered practically impossible or at least improbable.

In the accompanying drawings,

Figure 1 is a vertical sectional view 90 through the face of the mine wall and illustrating the application of my device within the usual needle hole, the device being shown in side elevation;

Figure 2 is a longitudinal sectional view 95 through the device;

Figure 3 is a view, similar to Figure 2 but taken at an angle of 90° thereto, and,

Figure 4 is a vertical section on the line 4—4 of Figure 3.

Referring more specifically to the drawings by numerals of reference, 2 indicates a 100 coal-bearing strata or the wall of a mine, 4 the packing of the bore-hole 6, which packing is usually of dirt and 8 the needle-hole which communicates with the blast or explosive charge.

Specifically my device which may be termed an isolator is formed from a metal tubular section of material 10, usually ordinary piping, about a foot in length and, its 110 outside diameter at its central portion being about one half inch while the inside diameter

is substantially one quarter inch throughout its length.

For a portion of its length, preferably that portion lying between two points spaced 5 approximately four inches from each end of the tube, the device is of uniform external diameter, as at 12, while the ends are tapered as at 14, to a diameter at their extremities, such that either may be inserted within the 10 needle hole 8, which at its opening is approximately three-eighths of an inch in diameter.

The central portion of uniform diameter is provided with two series of diametrically 15 transverse apertures 16 and 18 the two series being arranged respectively at right angles from each other and affording communication between the bore of the tube and the atmosphere for the escape of the gases which 20 pass from the needle hole. The apertures 16 and 18 are further so arranged that those of one series are longitudinally offset from or alternate with those of the other series.

In actual practice the squib or fuse is inserted into the outer end of the tube, with the match end protruding a distance of three or more inches. The end of the tube being spaced at least nine inches from the face of the wall permits of a distance of about 30 four inches of perforations to be utilized for the exit of the combustible gases which would otherwise pass to the point of ignition of the match end of the fuse. Therefore, there are no gases in the vicinity of the

match end. When lighted, the match end 35 slowly burns, giving the operator time to get a safe distance away before ignition of the powder portion of the fuse takes place. When the latter occurs, the fire passes inwardly through the tube and through the 40 needle-hole to fire the blast.

Having thus described the construction and manner of using my device, what I claim as new and desire to protect by Letters Patent is:

1. An isolator for use in firing blasts, comprising a tubular member adapted to be inserted within the mouth of a needle hole, said tubular member being provided with 50 perforations intermediate its ends.

2. An isolator for use in firing blasts, comprising a tubular member provided intermediate its ends with a series of transverse openings communicating with the bore of said tubular members.

3. An isolator to gas comprising a metal tubular member provided intermediate its ends with a longitudinal series of transverse openings passing through the wall of said tubular member, said tubular member being 60 tapered toward one end.

4. An isolator to gas comprising a metal tubular member tapered at each end and provided intermediate its ends with a longitudinal series of radial openings penetrating 65 the wall of said tubular member.

In testimony whereof I affix my signature.

WILLIAM HIER.
